United States Patent Office.

JOSEPH BUSSE, OF TROY, OHIO.

Letters Patent No. 91,518, dated June 22, 1869.

IMPROVED WOODEN WALL FOR BUILDINGS.

The Schedule referred to in these Letters Patent and making part of the same.

To all whom it may concern:

Be it known that I, JOSEPH BUSSE, of Troy, in the county of Miami, and State of Ohio, have invented a new and improved Mode of Constructing Wooden Walls for Buildings; and I do hereby declare that the following is a full, clear, and exact description thereof, reference being had to the accompanying drawings, making part of this specification, in which—

Figure 1 is a view of the inner side of my improved wooden wall, showing laths, or strips of wood or metal fastened to it.

Figure 2 is a vertical cross-section of the wall when plastered.

Figure 3 is a view of the inner side of a wooden wall differing slightly from that shown in figs. 1 and 2.

Figure 4 is a cross-section, taken vertically through this wall, plastered.

Figure 5 is a perspective view of a portion of a chambered wall, with dovetailed tenons on its inner surface.

Similar letters of reference indicate corresponding parts in the several figures.

On the 19th day of November, 1867, Letters Patent of the United States were granted to me for an improved method of constructing wooden walls, of planks laid flatwise upon each other, and arranged so as to leave ribs and grooves upon the inner side of the wall. The outer edges of the planks were bevelled, so as to give to the external surface of this wall the appearance of clapboards, siding, or weather-boards, and to shed water properly.

In carrying into practice this mode of making walls, I have found it objectionable, on account of the impracticability of making plastering adhere to their ribbed and grooved surfaces.

The nature of the invention which I have made, to remedy the objection above stated, consists in so constructing a wooden wall of planks laid flatwise, that its interior surface will present interlocking spaces which will receive the plaster used to cover this surface, and afford means for permanently holding the plaster, said planks being bevelled on their outer edges, so as to give the wall the appearance of being clapboarded, and to cause it to shed water freely, as will be herein-after explained.

The invention also consists in constructing such wall of alternate wide planks and narrow strips, arranged so as to leave horizontal chambers between the wide pieces or planks, in which chambers sand or other suitable substance is packed, for rendering the wall solid, and impervious to air and moisture, as will be herein-after explained.

To enable others skilled in the art to understand my invention, I will describe its construction and operation.

In the accompanying drawings, figs. 1 and 2, I have represented a portion of a wooden wall which is composed of alternate layers of wide planks, A, and nar-

row strips, B B', secured together, so as to form horizontal chambers, C, which are filled with fine sand, or other suitable material, which will not only solidify the wall, but will also pack the joints between the planks A and the interposed strips B B', so as to exclude air and moisture.

The planks and strips B A have their outer edges bevelled, as shown at a a, for giving a neat finish to the external surface of the wall, and also for shedding water from the joints or seams, as shown in fig. 2.

The planks A and strips B' have their inner edges grooved, so as to leave ribs, or tongues, b, upon these edges, as shown in figs. 1 and 2.

Diagonally across these ribs and grooves, wooden laths, or narrow strips, c, of metal, are nailed, and arranged in lines parallel to one another, at suitable distances apart.

If used alone, the grooves and ribs on the inner surface of the wall would not permanently support the plastering D, but with the addition of the strips c, arranged as described, prevent the plaster from becoming loose, in consequence of the latter working in the spaces between the strips c and the backs of the grooves, and thus keeping itself to the wall.

Instead of using the strips c, in combination with the horizontal ribs b, the half-dovetail tenons b', shown in figs. 2 and 3, may be adopted. These tenons are formed, by suitable machinery, upon the inner edges of the planks A', or upon the planks A and inner strips B', and afford horizontal under-bevelled grooves, which will receive the plaster D, and allow it to attach itself firmly to the wall.

In the figures last referred to, the planks A' are all of a uniform width, and their outer edges are bevelled in the same manner as the planks A and strips B above described.

I consider the dovetail or under-bevelled tenons b', as the equivalent of the perpendicular-faced tenons b, combined with the oblique strips c, inasmuch as both plans afford interlocking supports for holding the plastering firmly to the wall.

Having described my invention,

What I claim as new, and desire to secure by Letters Patent, is—

1. The construction of the inner surface of a plank wall, which has its planks laid flatwise of tenons b, and crossing strips c, substantially as and for the purpose described.

2. The bevelled and grooved planks A, in combination with the interposed strips B B' and horizontal chambers C, substantially as and for the purposes described.

JOSEPH BUSSE.
